SCREW DRIVER

Filed Aug. 14, 1937

FIG. 11.

INVENTOR
SETH J. COX
BY
Edward R. Inman
ATTORNEY

UNITED STATES PATENT OFFICE

2,185,910

SCREW DRIVER

Seth J. Cox, Franklin, Pa.

Application August 14, 1937, Serial No. 159,058

1 Claim. (Cl. 145—52)

This invention relates to improvements in screw drivers, and especially that class of screw drivers shown in Letters Patent of the United States, No. 1,412,550, dated April 11, 1922, and No. 1,562,543, dated November 24, 1925, both of which I am the sole owner.

The implements to which said patents respectively relate, are adapted for the sole purpose of screw drivers, whereas the invention described and claimed in this application is adapted for use with many other types of accessories in addition to screws, and as another improvement and advantage, the bit of the present invention is adapted to be manipulated in respect to its longitudinal movement within its tubular casing or shank, and to cause the consequently-accompanying opening and closing of the jaws, by the same hand which grasps the handle; whereas in the former constructions, the bit is not adapted to be moved by the same hand which grasps the handle of the tool. Furthermore, in the present invention, the bit may be provided with any suitably-formed point which is adapted to engage and to revolvably actuate any screw-threaded device, or accessory, that is provided with a slot, a socket, a tang or equivalent feature, adapted to be engaged and revolvably actuated by said point, or the equivalent thereof.

However, notwithstanding these improvements, the present implement is herein still designated as a screw driver, for convenience of classification, and a sufficiently close designation as to utility.

The construction of my improved screw driver is clearly illustrated in the accompanying drawing, in which:

Fig. 1 is a side view of my improved implement with the jaws thereof in their outermost, open position, and illustrating the new, or one-hand actuator for said bit and the associated jaw-member, both of which are adapted to move longitudinally within their tubular shank or casing.

Fig. 2 is a side elevation showing, in assembled relation, and removed from the tubular casing, the bit, the jaws, and the actuating stem, which stem extends from the inner end of said jaws into or adjacent to the handle of the implement.

Fig. 3 is a view of the adjacent side of Fig. 2, with the near jaw removed to illustrate more clearly the connected relation between said stem and the return end of said jaws.

Fig. 4 is an illustration in which the tubular casing of the implement is shown in longitudinal section, with the bit, its associated jaws and the actuating stem shown in elevation, and at the

outermost limit of their movement; the handle is omitted from this view.

Fig. 5 is a view partly in elevation and partly in section showing the bit and jaws in actuating engagement with a screw; a tubular slide is also shown in this view the function of which is the longitudinal actuation of the stem and the thereto attached bit and jaws; this is a modified form of actuator, as compared with the actuator illustrated in Fig. 1.

Fig. 6 is an end view of the adjacent end of Fig. 4.

Fig. 7 illustrates an implement provided with a bit 1^a adapted to engage and remove the cap of the well-known form of valve stem for pneumatic tires.

Fig. 8 and Fig. 9 are a side view and an end view, respectively, of the form of bit shown in Fig. 7.

Fig. 10 illustrates a bit 1^c in actuating relation with the type of valve which may be removed from the stem shown in Fig. 7 after the cap is removed in the manner thereshown.

Fig. 11 illustrates the type and form of end of the bit 1^c shown in Fig. 10.

Fig. 12 and Fig. 13 are a side view and an end view, respectively, of the form of bit 1^b adapted for the actuation of a socket set screw having a hexagonal socket, but other forms of socket and corresponding bit points or tangs are equally within the scope of my inventive idea.

The implement shown in the drawing comprises certain details which are assembled and cooperate in the following manner:

The form of bit which is adapted for use with a screw having a slotted head is indicated by the numeral 1; it is rectangular in cross section, and is provided with a clearance 2 for occupancy by a stop-projection 3, formed from one side or leg of the bifurcate jaw structure and projecting laterally, inwardly therefrom into said clearance for the purpose of preventing accidental displacement of the bit and limiting the relatively longitudinal movements thereof with respect to said jaw structure by contact with the end walls 3' of the clearance 2; said jaw structure is a unitary bifurcate element composed of spring steel, the free ends of which are formed into the inwardly-projecting jaws 4, 4; the rearward, junctional end 5 of said jaws connects them together at a right angle thereto, so as to form a square, closed, inner end, the object of which will presently appear.

One edge of said head 5, of said jaws, is removed as shown at 7 in Fig. 3, to facilitate the

engagement of the remaining portion of said head 5, by the adjacent portion of said stem 6, there being a transverse slot 6' extending across said stem for the reception of said remaining said stem for the reception of said remaining head-portion, and the longitudinal actuation of said jaw-structure.

Said jaws and actuating stem are mounted within a tubular casing 8, in which they are adapted to have longitudinal movement for the purpose of extending and opening said jaws to receive a screw or other element therebetween, and then to retract and close said jaws to engage said element, and to retain the same in revolvably actuating engagement with the related end of said bit 1, as shown in Fig. 5.

In the previous forms of this implement, as disclosed in the patents designated, it is necessary to actuate the bit into its element-engaging position by pushing the same inwardly, at the same time and with the element or screw that is to be engaged thereby, thus making it necessary for the user to use both hands in using and manipulating the implement; in the present form, the stem 6 is provided, which extends rearwardly into actuating proximity to the handle 9, and at said proximity, a longitudinally-extending slot 10 is formed through said casing 8, and a short section of casing 11, having an internal diameter or dimensions, such as to adapt it to be mounted upon and to slide easily longitudinally of said main casing, is supplied, as shown at 10 in Fig. 5; or instead of this construction, the ferrule, as 11' of the manipulating handle 9, may be supplied with a longitudinally disposed slot 10'; in either case, a suitable engaging pin or screw as 12, carried by said section or said ferrule is arranged in actuating relation to said stem, and by this means the thumb of the user of the implement which grasps the handle, may be employed to cause the

longitudinal movement of said stem, and thereto attached jaws; by this arrangement a one-hand implement is provided.

It is not my intention to confine this invention to a form of bit for use with the common form of wood screw, since any of the other forms of bit shown in the drawing having a modified form of point, may be readily substituted.

By the omission of the stop-projection 3, and the substitution of a readily removable screw 16 in place thereof the bits may be thereby adapted for ready removability, and replacement by other bits having a point of a different form, such as are shown in the drawing, or variations thereof as may be desired.

I claim the following:

A tool of the screw driver type comprising a hollow tubular shank of rectangular cross section having a hand grip on one end and being open at its other end, a jaw member of unitary bifurcate form slideable longitudinally in and through the open end of the shank and having a head disposed within the shank, a bit of rectangular cross section slideable longitudinally in and through the open end of the shank between the legs of said jaw member, cooperative means on said jaw member and bit for limiting relative longitudinal movement therebetween, a stem of rectangular cross section slideable longitudinally in said shank and extending from said jaw member substantially to said hand grip, said stem having a socket in its bit-adjacent end, the head of said jaw member being seated in said socket whereby the stem and jaw member are connected for movement longitudinally as a single unit, and actuator means on said stem and projecting laterally through said shank immediately adjacent said grip portion.

SETH J. COX.
